BINOCULAR ADJUSTMENT KNOB

Class O. Huckenbeck, Sherman Oaks, Calif., assignor to
Bausch & Lomb Incorporated, Rochester, N.Y.

Filed Apr. 30, 1975, Ser. No. 573,582

Term of patent 14 years

Int. Cl. D16—66

U.S. Cl. D16—43

FIG. 1 is a top plan view of a binocular adjustment knob showing my new design;

FIG. 2 is an elevation looking in the direction of line 2—2 of FIG. 1;

FIG. 3 is an elevation looking in the direction of line 3—3 of FIG. 6;

FIG. 4 is an elevation looking in the direction of line 4—4 of FIG. 1;

FIG. 5 is an elevation looking in the direction of line 5—5 of FIG. 2;

FIG. 6 is a bottom plan view looking in the direction of line 6—6 of FIG. 2;

FIG. 7 is a perspective view thereof;

FIG. 8 is a perspective view of a second modified embodiment of the knob illustrated in FIG. 7; and

FIG. 9 is an end view of the knob illustrated in FIG. 8.

The broken lines representing the binocular are shown for illustrative purposes only.

I claim:

The ornamental design for a binocular adjustment knob, substantially as shown and described.
